Des. 184,877
Patented Apr. 14, 1959

184,877

COMBINED PLANTER BOWL AND STAND

Jack Kaye, New York, N.Y., assignor to Abco Metal Creations, Inc., New York, N.Y., a corporation of New York

Application March 4, 1958, Serial No. 49,895

Term of patent 3½ years

(Cl. D35—3)

Fig. 1 is a front elevational view of a combined planter bowl and stand, showing my new design;

Fig. 2 is a side elevational view;

Fig. 3 is a top plan view of the same; and

Fig. 4 is a vertical sectional view taken on the line 4—4 of Fig. 1.

I claim:

The ornamental design for a combined planter bowl and stand, substantially as shown.
